GEORGE A. JOHNSON, OF CHICAGO, ILLINOIS, ASSIGNOR TO WILLIAM H. MINER, OF CHICAGO, ILLINOIS.

DRAFT-RIGGING FOR RAILWAY-CARS.

1,128,321.

Specification of Letters Patent. Patented Feb. 16, 1915.

Application filed May 21, 1913. Serial No. 768,986.

To all whom it may concern:

Be it known that I, GEORGE A. JOHNSON, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of simple construction and efficient operation.

In the drawings forming a part of this specification Figure 1 is a side elevation partly in longitudinal vertical section on line 1—1 of Fig. 2 of a draft rigging embodying my invention. Fig. 2 is a plan view partly in horizontal section on line 2—2 of Fig. 1. Fig. 3 is a plan view partly in horizontal section illustrating the position of the parts of the draft rigging when under full compression in pulling movement. Fig. 4 is a plan view partly in longitudinal section illustrating the position of the parts of the draft rigging when under full compression in buffing movement.

Referring to the drawings 6, 6 represent draft sills or parts of the car frame to which the draft rigging is applied, 7 the end sill, 8 the buffer block, 9 the draw bar carry iron, 10 the tie plate adapted to support the draft gear and suitably secured to the draft members, preferably by the bolts 11, 11, 12 the draw bar connected to the draft yoke 13, 14, 14 the rear stop members provided with the stop shoulders 15, 15, 16, 16 the front stop members each provided with a slot or recess 17, the said slots being in opposed relation to each other between the draft members 6, 6, and adapted to receive the ends of the front follower 18 hereinafter described.

The draft gear 19 is mounted within the draft yoke and comprises a shell 20, preferably a hollow cylinder in form, open at its front end and closed at its rear end by the preferably integral plate 21 having the lateral projections 22, 22 adapted to engage the rear stop shoulders 15, 15 in performing the functions of a rear follower. Within the

shell are the friction members 23 and spring members 24. The spring members preferably comprise an outer spring 25 and an inner spring 26 nested therein, the said springs being rearwardly seated against the shell and forwardly seated against the friction members. The friction members 23 comprise the friction shoes 27, the wedge 28, and in preferable construction the antifriction rollers 29 interposed between the wedge and the friction shoes. The friction shoes 27 are preferably three in number, and in annular arrangement, each having an outer friction face 30 adapted to frictionally engage the inner surface of the shell, and the inner wedging face 31, provided in preferable construction with a transverse antifriction roll seat 32. The wedge is provided near its inner end with the wedging faces 33, there being one for each friction shoe, and in preferable construction one antifriction roller is seated between each wedging face of the wedge and a friction shoe. The wedge 28 is forwardly extended, and adapted to pass through an opening 34 through the front follower to engage at the forward face 35 of the wedge with the rear face 36 of the draw bar 12. The wedge is provided with a recess 37 to receive the head 38 of the connecting rod 39 which passes through a perforation 40 in said wedge, and through a perforation 41 in the rear end of the shell, the said rear end of the shell being provided with a recess 42 to receive the nut 43 of said connecting rod.

The novel features of my invention consist in the direct engagement between the draw bar and wedge provided for in the construction described, in the form of wedge employed, the form of front follower employed, the means of engaging the front follower to the front stop members, and in the stationary position of the said front followers and other particular features of its construction.

The front follower is stationary in both forward and rearward movement of the draw bar. In forward movement of the draw bar the friction shoes at their forward ends engage the rear face of the front follower. The springs within the shell being seated between said friction shoes and the rear end of the shell are on forward move-

ment of the yoke and of the shell compressed against the friction shoes, which remain stationary, and which by reason of the wedge not being stopped against the front follower or otherwise, and not subjected to spreading action, are consequently not employed in frictional action on forward movement of the draw bar. In such forward movement the limit of compression of the springs is obtained when the forward end of the shell engages the front follower, as illustrated in Fig. 3 of the drawings. It will be obvious that the action of the gear is a spring action only on forward movement of the draw bar, and that the release action in the return of the parts to normal position after compression in pulling movement will be an easy return without rebounding of the spring.

On rearward movement of the draw bar the shell is stationary against the rear stop members, and the wedge is forced rearwardly without the interposition of the front follower in the action spreading the friction shoes and forcing the same rearwardly, compressing the springs within the shell until on complete rearward movement of the parts the friction shoes are compressed within the shell and the rear end of the draw bar engages the front face of the front follower 18, as illustrated in Fig. 4 of the drawings.

I claim:

1. In a draft rigging for railway cars, in combination, a draw bar, stop members, a front follower, a shell, friction shoes and wedge within the shell, the front follower having an opening therethrough for the passage of the wedge, the said wedge being adapted to directly engage the draw bar on rearward movement thereof.
2. In a draft rigging for railway cars, in combination, a draw bar, stop members, a draft yoke, a shell, springs, friction shoes and wedge within the shell, and a front follower, the front follower being stationary in both pulling and buffing movement of the draft rigging, and having an opening therethrough for the passage of the wedge.
3. In a draft rigging for railway cars, in combination, a draw bar, stop members, a draft yoke, a shell, springs, friction shoes and wedge within the shell, the front follower being stationary and having an opening therethrough for the passage of the wedge, the friction shoes engaging the front follower and being stationary in relation thereto on forward movement of the shell.
4. In a draft rigging for railway cars, in combination, a draw bar, stop members, followers, a shell, springs, friction shoes and wedge within the shell, the wedge being actuated independently of the front follower, and the friction shoes and the front

follower being in engagement with each other and stationary in relation to the stop members on forward movement of the draw bar.

5. In a draft rigging for railway cars, in combination, stop members, a draw bar, a draft yoke, a shell, springs, friction shoes and wedge within the shell and a stationary front follower, the wedge passing through the front follower, the friction shoes being stationary in relation to the front follower on forward movement of the shell, and in such movement acting as a seat against which the springs are compressed.

6. In a draft rigging for railway cars, in combination, a draw bar, a shell, a draft yoke, a front follower, springs, friction shoes and wedge within the shell, the wedge passing through the front follower and being adapted to spread the friction shoes on rearward movement, and to exert no spreading action on forward movement of the draw bar.

7. In a draft rigging, in combination, a draw bar, stop members, a draft yoke, a shell, springs, friction shoes and wedge within the shell, the said wedge being adapted to act independently of the front follower and to spread the friction shoes only on rearward movement of the draw bar.

8. In a draft rigging for railway cars, in combination, a draw bar, a draft yoke, a shell, springs, friction shoes and wedge within the shell, front and rear stop members and followers, the front stop members being provided with recesses to receive the front follower in its stationary position therein, the front follower being provided with an opening for the passage of the wedge therethrough, the said wedge being adapted to act independently of said follower, and to spread the friction shoes only on rearward movement of the draw bar.

9. In a draft rigging for railway cars, the combination of a draw bar, a shell, a stationary front follower and means for connecting the shell to the draw bar, of compression resisting members within the shell comprising springs, friction shoes and a wedge, the said wedge being in direct engagement with said draw bar, said front follower being located between the friction shoes and the rear end of the draw bar.

10. In a draft rigging for railway cars, the combination with a draw bar, friction shell, and means for connecting the shell to the draw bar, of a stationary follower, friction shoes and springs mounted within said shell, said shoes and springs being located on one side of the stationary follower, a wedge co-operable with said shoes, and means for operating the wedge upon movement of the draw bar in one direction only, the wedge being inactive in movement of

the draw bar in the opposite direction and said shoes being held stationary by said stationary follower during such movement.

11. In a draft rigging for railway cars, 5 the combination of a draft gear comprising a shell, friction shoes, a wedge and springs within the shell, with a seat against which the friction shoes engage on forward move-

ment of the shell, said seat being adapted for the passage of the wedge, said wedge 10 being operative independently of said seat.

GEORGE A. JOHNSON.
